UNITED STATES PATENT OFFICE.

BYRON PHELPS, OF SEATTLE, WASHINGTON.

LOCK MECHANISM.

No. 838,808.

Specification of Letters Patent.

Patented Dec. 18, 1906.

Application filed April 14, 1905. Serial No. 265,477.

To all whom it may concern:

Be it known that I, BYRON PHELPS, a citizen of the United States, residing at Seattle, King county, State of Washington, have invented certain new and useful Improvements in Lock Mechanism, of which the following is a full, clear, and exact description.

My invention relates to improvements in lock mechanism. Letters Patent No. 769,769, granted me September 13, 1904, illustrates lock mechanism of the same general character.

The improvements herein referred to relate more particularly to an improved form of dogging device, or night-latch and setting mechanism therefor.

In the drawings, Figure 1 shows a lock mechanism embodying my invention as applied to a fragment of the edge of a door. Fig. 2 is a plan view of the lock mechanism with the night-latch and showing part of the construction in cross-section, the outer knob being locked. Fig. 3 is a plan view showing the parts released so that the latch-bolt may be operated by either knob. Fig. 4 is a cross-sectional view showing certain details of construction in elevation.

In the particular form shown herein the latch-bolt is operated by two knobs, the outer one of which carries a cylinder-lock for permitting the retraction of the latch-bolt when the outer knob itself is dogged or locked against rotation. The "night-latch" mechanism, so called, is set and released alternately by giving to the latch-bolt a supplemental or abnormal repression beyond the face of the end plate. The limit of the normal repression of the latch-bolt produced by the closing of the door at which time the latch-bolt encounters the usual striker-plate is represented by the face of the end plate through which said latch-bolt projects. It is by manually repressing the latch-bolt itself to a still greater extent when the door is open that the night-latch mechanism or dogging mechanism is set or released. By this means the latch-bolt will be seen to perform two functions—to wit, first, the usual one of holding the door when closed, and, second, the novel one of serving as an operating means

when the door is open for permitting the user to throw the night-latch or dogging mechanism into or out of action.

1 is the fragment of the door to which the lock is attached.

2 and 3 are the inner and outer knobs, respectively.

4 and 5 are the inner and outer escutcheon-plates.

6 is a frame carrying the operating mechanism.

7 is the end plate of the frame.

8 is the latch-bolt pivoted to the frame.

9 and 10 are the shanks of the inner and outer knobs, respectively.

11 and 12 are tubular extensions from the frame 6, serving as guides and supports for the knob-shanks.

13 is the latch-slide.

14 is a spring for normally extending the latch-bolt.

15 and 16 are roll-backs operated by the inner and outer knob-shanks, respectively.

17 is the spindle of a cylinder-lock, which extends freely through an enlarged opening in the roll-back 16, but fitting into the roll-back 15 serves to operate the latch-slide through the medium of the inner knob-shank when the outer knob-shank is dogged and the lock-plug is turned, as customary, by means of a key.

18 is a dogging-bolt slidable in a portion of the frame 6 and adapted to fit into a recess or opening in the outer knob-shank 10 for preventing the rotation of the same when it is desired to lock the door.

19 is a slide for the dogging-bolt suitably guided in the frame.

20 is a tilting-lever pivotally carried by the frame 6 and having a slotted portion engaging a pin 21, carried by the dogging-slide 19.

22 and 23 are arms pivotally carried by the tilting-lever 20 and normally resting upon the bridge 24, which supports their outer ends.

25 is a spring for holding the operating-arms 22 and 23 yieldingly in position.

26 and 27 are inclined projections carried

by the operating-arms 22 and 23, respectively, which are adapted to mutually coöperate with each other.

28 is a spring for engaging in one of two notches in the tilting-lever 20 for holding the tilting-lever definitely in either the position shown in Fig. 2 or that shown in Fig. 3, with the dogging-bolt engaging the outer knob-shank or disengaged therefrom, as is desired.

When the parts are in the position shown in full lines in Fig. 3, the latch-bolt may be retracted by the operation of either knob, the dogging-bolt 18 being retracted. The dogging-bolt may, however, be thrown into engagement with the outer knob-shank by simply pressing in the latch-bolt 8 beyond the face of the end plate into the position shown in full lines in Fig. 2. Such operation causes the back of the latch-bolt to engage the end of the arm 23 and tilt the lever 20 to force the dogging-slide 19 and dog 18 into the position shown in Fig. 2. As the arm 23 moves inward the arm 22 is moved outward, and the inclined member 26 rides up the upper surface of the inclined member 27, so as to raise the outer end of the arm 22 above the upper edge of the latch-bolt 8 and free therefrom. When the latch-bolt is released, it returns to its outwardly-protruding position by virtue of the pressure of the spring 14 and permits the arm 22 to fall to its normal position. When it is desired to release the dogging-bolt 18, the latch-bolt 8 is again pressed inward, engaging the end of the arm 22, which is thus moved inward. The incline 27, riding up the incline 26, raises the arm 23 clear of the latch-bolt 8, permitting the full inward movement of the latter for releasing the dogging-bolt, as shown in Fig. 4.

The operation and construction of the mechanism are simple, and it has the particular advantage of small number of parts and inaccessibility to tampering. The ordinary closing of the door throws the latch-bolt 8 to position shown dotted in Fig. 3, which does not affect either of the tilting-arms 22 or 23.

What I claim is—

1. In a lock mechanism, the combination of a latch-bolt, operating means therefor, and a dogging device for said operating means and means operable by the latch-bolt for moving the dogging device, said dogging device being operable by a supplemental re-pression of said latch-bolt.

2. In a lock mechanism, a dogging device, a tilting lever, movable arms operatively connected thereto, a movable operating member adapted to alternately engage said arms to rock said tilting lever and move said dogging device into the locking and unlock-

ing position alternately, and operative connections between said dogging device and said tilting lever.

3. In a lock mechanism, an inner and an outer knob, a dogging device for the outer knob, a latch-bolt, and means of connection between said dogging device and said latch-bolt whereby by a supplemental movement of said latch-bolt said dogging device is actuated to lock or unlock said outer knob.

4. In a lock mechanism, a dogging device, a pair of movable arms, coöperating projections carried by said arms, operative connections between said arms and said dogging device, and a movable operating member co-acting with said arms to alternately move said dogging device into the locking and unlocking position.

5. In a lock mechanism, a dogging device, a tilting lever operatively connected therewith, a pair of arms carried by said tilting lever on opposite sides of the center, inclined coöperable portions carried by said arms, and manually-controlled operating means for engaging said arms to tilt said lever, said inclines coöperating to free one of said arms while the other is being repressed by said manually-controlled operating means.

6. In a lock mechanism, a latch-bolt, two independent knobs coöperating therewith, a dogging device arranged to lock and unlock one of said knobs, a tilting lever operatively connected with said dogging device, a pair of arms connected to said tilting lever on opposite sides of the center, said arms being arranged to be operated by said latch-bolt alternately upon the abnormal repression of said latch-bolt.

7. In a lock mechanism, a spring-pressed latch-bolt, means for retracting the same, a dogging device for said retracting means, and operative connections between said latch-bolt and said dogging means whereby the latter may be operated by a supplemental movement of said latch-bolt.

8. In a lock mechanism, a spring-pressed pivoted latch-bolt, means for retracting the same, a dogging device for said retracting means, and operative connections between said latch-bolt and said dogging means whereby the latter may be operated by a supplemental movement of said latch-bolt.

9. In a lock mechanism, the combination of a latch-bolt, operating means therefor, a dogging device for said operating means, and means for setting the dogging device in the locked position by a supplemental manual operation of the latch-bolt.

10. In a lock mechanism, the combination of a latch-bolt, operating means therefor, a dogging device for said operating means, and

means for releasing the dogging device from the locked position by a supplemental manual operation of the latch-bolt.

11. In a lock mechanism, a latch-bolt, a knob, operative means of connection between said latch-bolt and said knob, a dogging device for preventing the retraction of said latch-bolt by said knob, and means for operating said dogging device, said means being operated by a supplemental manual operation of the latch-bolt.

12. In a lock mechanism, a latch-bolt, a

knob on each side of the lock, said knobs being operatively and independently connected with said latch-bolt, a dogging device for preventing the retraction of the latch-bolt by the rotation of one of said knobs, and means for operating said dogging device, said means being operated by a supplemental manual operation of the latch-bolt.
